UNITED STATES PATENT OFFICE.

HARRY COLER STREEPER, OF BRISTOL, PENNSYLVANIA.

INCLOSURE FOR BOILERS AND HEATERS.

1,262,713.

Specification of Letters Patent. Patented Apr. 16, 1918.

Application filed February 23, 1917. Serial No. 150,309.

To all whom it may concern:

Be it known that I, HARRY C. STREEPER, a citizen of the United States, residing at Bristol, in the county of Bucks and State of Pennsylvania, have invented certain new and useful Improvements in Inclosures for Boilers and Heaters, of which the following is a specification.

My invention consists of an improved inclosure for boilers and heaters. One object of my invention is to prevent the hot gases of combustion from passing directly from the boiler or heater up the chimney.

Another object of my invention is to so construct my improved inclosure that said hot gases will be compelled to pass entirely around and in contact with the outer surface of the boiler or heater prior to passing up the chimney, and thus retain the heat within the boiler or heater at a high temperature.

Another object is to so construct my invention that it can be readily adapted to fit various types of boilers and heaters now on the market and in common use.

A further object is to make my invention of simple construction and so that the parts thereof can be easily removed for repair or cleaning purposes.

These objects, and other advantageous ends which will be described hereinafter, I attain in the following manner, reference being had to the accompanying drawings in which

Figure 1 is a front elevation of my invention attached to a heater such for example as a hot water heater of a type now in common use for heating buildings.

Fig. 2 is a section on the line 2—2 of Fig. 1.

Fig. 3 is a section on the line 3—3 of Fig. 2 showing the heater in outside elevation.

Fig. 4 is a transverse section on the line 4—4 of Fig. 1.

Fig. 5 is a transverse section on the line 5—5 of Fig. 1.

Fig. 6 is a perspective view of one of the side baffle plates which forms a part of my invention.

Fig. 7 is a fragmentary sectional elevation showing a modification of my invention, and

Fig. 8 is a transverse section on the line 8—8 of Fig. 7.

Referring to the drawings, the body portion 1 of the heater is supported on a base 2 which is preferably made hollow to re-

ceive the ashes and is provided with a door 3 which covers an opening 4 through which the ashes may be removed from time to time.

The usual fuel supply opening 5 is provided, as well as the opening 6, through which clinkers may be removed from the grate level of the heater. The upper portion of the heater in the present instance is provided with an opening 7 which forms an outlet for the hot gases and other products of combustion, this being the opening which is ordinarily attached to the chimney by a pipe including a damper to regulate the draft. However, in my present invention I eliminate this direct connection between the opening 7 and the chimney as will be more clearly understood from the following description.

The base 2 forms a support for a jacket 8 which is substantially cylindrical and includes a front section 9 and a rear section 10. This jacket is of substantially greater internal diameter than the external diameter of the body portion 1 of the heater and is also of greater height, thus providing a chamber 8^a which surrounds the body portion as clearly shown in Fig. 2.

The top of the jacket 8 has secured to it by bolts 11, a cover 12 which in the present instance is circular in shape and is perforated at 13 to permit the water circulating pipes 14 of the heater to extend therethrough.

The sections 9 and 10 have outwardly projecting flanges 15 and 16 respectively between which are secured two longitudinally extending baffle plates 17. These baffle plates are arranged diametrically opposite in the present instance and have their outer edge portions 18 extending the full length of the flanges 15 and 16.

Bolts 19 pass through the flanges 15 and 16 and also through the edge portions 18 of the baffle plates 17, thereby securing the latter and also joining the front and rear sections.

Each of the baffle plates 17 has a wing 20 which extends inwardly and into direct contact with the outer surface of the body portion 1 of the heater (see Figs. 1, 3, and 5). The wings 20 are of shorter length than the portions 18 and form passageways 21 between the compartment 22 of the section 9 and the compartment 23 of the section 10, it being noted that the provision of said baffle plates 17 divides the chamber 8^a into

the said compartments 22 and 23 and the passages 21 form communication between the compartments 22 and 23 adjacent the lowermost portion of the body 1 of the heater.

A segmental baffle 24 covers and forms a top for the upper portion of the compartment 23, and this baffle is in the form of a half ring, the ends 25 of which extend over the upper edges 26 of the baffle wings 20 (see Figs. 1, 2, 3, and 4). The edges 26 of said baffle wings 20 are substantially on a level with the top surface 27 of the heater body 1, so that an upper compartment 28 is provided between the cover 12 and the upper surface 27 of the heater body 1. The segmental baffle 24 has an opening 29 which is normally closed by a damper 30, the latter being pivotally supported on the baffle 24 and has a rod 31 which extends through the rear section 10 to the outside of said jacket and is provided with a handle 32, whereby the damper may be opened if desired.

The rear section 10 has an opening 33 which communicates with a pipe 34 which leads to the chimney, said pipe having a regulating damper 35. Another damper 36 is formed within the pipe 34 and when open, the pipe 34 will communicate with the atmosphere immediately surrounding the jacket 8, so that the intensity of the draft may also be regulated by the damper 36.

The front section 9 has an opening 37 for the reception of a sleeve 38, the latter having outer flanges 39 which abut the outer surface of the front section 9, said sleeve fitting within the fire door opening 5 within the body 1 of the heater, thus permitting fuel to be supplied to the heater and providing a seal to prevent the heated gases from escaping through the opening 37. In like manner, a sleeve 40 is inserted through an opening 41 adjacent the bottom 45 of the front section 9, said sleeve entering the clinker opening 6. This sleeve 40 is also provided with an outer flange 42 which limits the inward movement of the sleeve and also forms a seal to prevent the escape of gases.

A fire door 43 is hinged to the front section 9 and acts as a closure for the sleeve 38. In a similar manner, a door 44 forms a closure for the sleeve 40.

The operation of my invention is as follows:

The hot gases and products of combustion pass out of the opening 7 into the compartment 28, and since the segmental baffle 24 prevents them from passing directly through the pipe 34, they are compelled to pass forwardly in the direction of the arrows and downwardly through the compartment 22, it being noted that the wings 20 of the side baffle plates 17 prevent the

gases from passing into the compartment 23 until they have completely passed down the front half of the body 1 of the heater.

After passing to the bottom of said body portion 1 of the heater, they pass through the passages 21 and upwardly through the compartment 23, thence outwardly through the pipe 34. It will thus be noted that I secure a circulation of the heated gases entirely around and in contact with the outer surface of the body portion 1 of the heater prior to their passing to the chimney, thus the outer surface of the body portion 1 of the heater is kept extremely hot and adds to the efficiency of said heater in performing its function of circulating, in the present instance, the water through the pipes 14 and the water is kept at a higher temperature than if the heated gas was allowed to directly pass from the opening 7 to the chimney without first performing the function of providing a heating medium between the jacket and the outer surface of said body portion 1 of the heater.

If, for any purpose, it is desired to have a direct draft between the opening 7 and the chimney, the damper 30 may be opened and the movement of the gases will then be directly through the opening 29 and pipe 34 to the chimney.

In the modification shown in Figs. 7 and 8, I have shown a bottom 45 for the jacket. This bottom is designed to rest upon the base 2 of the heater and has an upwardly projecting flange 46 which is bolted to the lower edge portions of the jacket 8. The bottom 45 is preferably made in two sections to permit the edge portions 18 of the side baffle plates 17 to project therebetween as well as the flanges 15 and 16 of the jacket sections 9 and 10. This bottom 45 is of value when the base 2 of the heater is comparatively narrow as illustrated in Fig. 7, so that said bottom forms a projection or extension to provide the support for said jacket which must necessarily be of larger diameter than the body portion 1 of the heater.

The advantage of my invention is two-fold. It keeps the heater proper at a higher temperature, and it also heats the surrounding atmosphere, and is therefore of exceptional value when attached to heaters in dwelling houses or other buildings which are located in the cellar, since it keeps the cellar warm and dry.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what

I claim as new and desire to secure by Letters Patent is:

1. The combination of a heater having an outlet opening for the products of combustion, a jacket surrounding said heater and spaced therefrom to provide a chamber, said jacket being made in a plurality of sections and having outwardly projecting flanges, baffle plates having outer edge portions secured between said flanges and having their inner portions extending across said chamber and into engagement with said heater, said latter portions of the baffle plates being interrupted in their length at opposite ends to divide the chamber into a number of compartments and to provide a passageway forming communication between the compartments at a position remote from said outlet opening of the heater, another baffle connecting said baffle plates and forming a closure for certain of said compartments between said outlet opening of the heater and said remote passageway, said jacket having an outlet opening adjacent said second baffle, substantially as described.
2. The combination of a heater having an outlet opening for the products of combustion, a jacket surrounding said heater and spaced therefrom to provide a chamber, said jacket being made in a plurality of sections, said sections being detachably secured together, baffle plates having outer edge portions secured between said sections and having wing portions extending into engagement with said heater, a segmental baffle spaced below the top of the jacket extending from said wings and separating said outlet opening of the heater from one of said compartments, said jacket having an opening below the segmental baffle leading from said latter compartment, said baffle plates providing a passage between said compartments whereby the products of combustion are compelled to pass around and in contact with the outer surface of said heater prior to passing out of the opening in the jacket, substantially as described.
3. The combination of a heater having an outlet opening for the products of combustion, a jacket surrounding said heater and spaced therefrom to provide a chamber, said jacket being made in a plurality of sections, said sections being detachably secured together, baffle plates secured between said sections and having wing portions extending into engagement with said heater, a segmental baffle extending from said wings and separating said outlet opening of the heater from one of said compartments, said jacket having an opening below the segmental baffle and leading from said latter compartment, said baffle plates providing a passage between said compartments whereby the products of combustion are compelled to pass around and in contact with the outer surface of said heater prior to passing out of the opening in the jacket, said segmental baffle having an opening therein above the space between the outer side of the heater and the inner side of the jacket, and a damper for normally covering said opening, substantially as described.

In testimony whereof I have signed my name to this specification in the presence of two subscribing witnesses.

HARRY COLER STREEPER.
